UNITED STATES PATENT OFFICE.

LUKE PATTERSON WOOD, OF UNIONTOWN, PENNSYLVANIA.

CABLE-ROLLER BRACKET.

1,409,807.

Specification of Letters Patent. Patented Mar. 14, 1922.

Application filed December 19, 1921. Serial No. 523,484.

To all whom it may concern:

Be it known that I, LUKE PATTERSON Wood, a citizen of the United States of America, residing at Uniontown, in the 5 county of Fayette and State of Pennsylvania, have invented certain new and useful Improvements in Cable-Roller Brackets, of which the following is a specification.

This invention relates to an improvement 10 in brackets designed for the support of the cable carrying rollers, used in mine and similar haulage systems.

The invention is particularly directed 15 to a bracket, with which the roller proper may be readily associated, which bracket is formed with means for guiding a displaced cable portion back onto the roller without liability of undue wear on the bracket or cable; the mounting of the roller in the 20 bracket being such as to permit the convenient use of a self-oiling system for the roller.

The invention is illustrated in the accompanying drawings, in which:

25 Fig. 1 is a perspective view illustrating a roller and the bracket mountings therefor constructed in accordance with the present invention.

Fig. 2 is a broken perspective of one end 30 of the roller, showing the bearing bracket and oiling ring arranged thereon.

Fig. 3 is a longitudinal section through the bearing bracket.

35 Fig. 4 is a transverse section of the same. As is usual in haulage systems of this type, each roller 1 is supported in bearing brackets 2, secured to transverse supports, as ties 3, the rollers being designed to support a moving cable 4 for use in hauling.

40 In cable hauling systems of this character, the necessity for slackness in the cable causes portions of the cable to frequently ride off of one or more of the supporting rollers, following which the cable in its tendency to return to the roller under strain on the cable, engages the bracket and tends to a breakage of such bracket or an undue wear 45 on the cable.

The present bracket is constructed with a 50 view to avoiding this wearing contact between the cable and bracket, in the attempt of the displaced portion of the cable to return to the roller, the means provided to this end serving to guide the cable onto the 55 roller without undue wear of the cable or bracket.

The improved bracket is formed with a hollow central box-like portion 5, open at the top and formed in the inner wall with a recess 6, through which the shaft 7 of the 60 roller 1 is adapted to extend. A cover 8 is adapted to overlie and close the box-like portion 5, said cover being pivotally connected at one end to an external ear 9 at one end of the box-like extension, and adapted to engage and be removably secured to a similar ear at the opposite end of the extension, thus 65 removably holding the cover in place.

The box-like extension 5 of the bracket is formed on its outer side, approximately in 70 line with the recess 6, with a guide extension 10, the bottom of which aligns with the bottom of the bracket, and the outer rounded guiding edge 11 of which extends upwardly and inwardly toward the bracket at approximately 45° to the vertical, the upper end of the guide extension terminating in line with the top of the box-like extension 5 of the bracket and forming therewith a slight shoulder 12. A cooperating guiding element 75 80 13 is carried by the cover, this cover guiding element having its lower end resting upon the shoulder 12 and its outer surface thereby aligned with the outer surface or guiding edge 11 of the guiding element 10. The 85 guiding element 13 has its guiding edge 14 upwardly and inwardly curved, this guiding edge terminating abruptly in line with the inner edge of the bracket proper and at a point above the roller 1. 90

Thus, in the event the cable is displaced at either side of the roller 1, as when the cable is slack, subsequent strain on the cable, tending to return the cable to its normal line of operation, that is, on the rollers 1, 95 will cause the cable to engage the particular guiding edges 11 and 14 of the elements 10 and 13, and thus be caused to readily return onto the rollers without undue wear on any portion of the bracket or cable. Obviously, 100 the guiding element 13 will be subjected to greater wear than the guiding element 10, as the cable in approaching the roller engaging position, is drawn more tightly than when engaging the lower guiding element 10. Thus, the guiding element 13 will wear more rapidly in use than the guiding element 10, and hence provision is made, through the removable connection of the guiding element 13 with the cover, for renewing this guiding element 13, as it may 110 become necessary.

The invention also contemplates a specific structure for supporting the shaft 7 within the box-like extensions 5, to take advantage of a well known continuous self-oiling system. In this use, the box-like extensions become oil receptacles, and are adapted to be readily filled with oil to the predetermined level by merely opening the cover 8.

The shaft 7 is supported at its ends in hanger plates 15, the upper plate-like portions of which are adapted to fit in the upper portions of the box-like extensions 5, the ends of the plate-like portions of the hangers being supported on shoulders 16 at the respective ends of the box-like extensions 5. The hangers also include rounded extensions 17 depending from the plate-like portions and formed with openings 18 to loosely receive the shaft 7. The plate-like portions of the hangers are formed with longitudinally extending slots 19, and the rounded extensions 17 are spaced apart in accordance with the transverse dimension of the slots. An oiling ring 20 is adapted to loosely surround the shaft 7, fitting between the extensions 17 and in the slot 19 of each hanger, this ring having a diameter sufficient to cause the lower portion thereof to extend into the body of oil below the shaft. This system of continuous oiling through the use of the ring described is well known in the art, but the combination of the ring of a hanger plate loosely supported in bearing box extensions, the said hanger plates serving as a means for limiting the endwise play of the ring, is a particular improvement in such oiling systems and forms a material part of the present invention.

The guiding element 13 is preferably removably secured and placed to the cover 8, by a screw 21, which extends from the inner side of the cover and threads into the guiding element. Of course, the lower edge of the guiding element 13 is shaped to accu-

rately fit the top of the cover 8, so that with the screw 21 fitted tightly in place, the guiding element 13 is removably held in alignment with the guiding element 10.

The inner edge of the hanger plates 15 immediately in line with and below the opening 18 is formed with a V-shaped depression 21, forming an oil channel leading from such opening 18. The oil dripping from the shaft or pin 7 is thus directed back into the reservoir rather than to permit it to escape on the outside of the housing.

Claims:

1. A bracket for supporting cable carrying rollers, including a hollow box-like extension to receive the shaft of the roller, a cover for closing said extension, a cable guiding element on the outer wall of the box-like extension, and a cable guiding element on the cover, the latter guiding element aligning with the first mentioned guiding element and terminating at the inner side of the bracket on a plane above the roller.

2. A roller bracket having a box-like extension to receive the shaft of the roller, a cover for such extension, a cable guide secured to the outer wall of the box-like extension, and a cable guide secured to said cover, the cable guide on the cover having a curved guiding surface and terminating on a plane above the surface of the roller.

3. A roller bracket having a box-like extension to receive the shaft of the roller, a cover for such extension, a cable guide secured to the outer wall of the box-like extension, and a cable guide removably secured to said cover, the cable guide on the cover having a curved guiding surface and terminating on a plane above the surface of the roller.

85

In testimony whereof I affix my signature.

LUKE PATTERSON WOOD.
